Assistant Examiner — Yelizaveta Y Masalimova

(57) CLAIM

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee.

1. Shoe

1.1 : Front

1.2 : Back

1.4 : Right

1.5 :Top

1.6 :Bottom

1.7:Perspective

1.8 : State of change

The drawings only show the design on the left shoe; the right shoe is omitted as it is symmetrical to the left shoe.

1 Claim, 8 Drawing Sheets
(8 of 8 Drawing Sheet(s) Filed in Color)
